UNITED STATES PATENT OFFICE.

CHARLES F. OXLEY, OF BROOKLYN, NEW YORK.

FRICITION-SLIDE.

SPECIFICATION forming part of Letters Patent No. 313,444, dated March 3, 1885.

Application filed May 31, 1884. (No model.)

To all whom it may concern:

Be it known that I, CHARLES F. OXLEY, of the city of Brooklyn, county of Kings, and State of New York, have invented a new and useful Improvement in Friction-Slides, of which the following is a full, true, and exact description, reference being had to the accompanying drawings.

My invention relates to an apparatus by means of which a slide or rod can be freely moved in one direction, while when it is moved in the opposite direction a friction or resistance is applied to its movement.

My invention is applied, as shown, to the slide of a chandelier; but it is manifest that it can be usefully applied to other structures besides the drop-tube of a chandelier.

That which is new in my invention will be pointed out in the claims hereto annexed.

My invention will be readily understood from the accompanying drawings, in which Figure 1 represents a vertical elevation, partly in section; and Fig. 2, a plan view of my pawl-carrying disk.

In the drawings, A represents a chamber, preferably cylindrical in section, containing the various parts of my friction device. The chamber A is supported upon the tube H by a screw-thread or other means, which holds it rigidly against rotation. The rod B, which in this case is the gas-tube, is twisted spirally, as shown, and is provided with one or more projecting ribs. As shown, four such ribs are provided. As applied to a chandelier the tube

B will slide vertically within the tube H, but is prevented from rotation therein by a suitable contrivance—as, for instance, the tube H may be hexagonal in section, and the tube B may be provided with a hexagonal nut sur-

rounding it and slide within the tube H. A gas-tight joint is likewise provided between the tube H and the tube B at the upper end of the tube B. Within the chamber or drum A is the circular shelf R. Beneath this shelf,

and fitted to engage therewith, is a frictional flanged disk. This disk C is pressed upward by the action of a spring, D. The lower end of this spring D bears against the cap or cover E, screwing upon the bottom of the drum A.

The disk C is provided with a central open-

ing large enough to permit the free passage of the tube B without rotating the disk, and, as shown, is provided with a lower flange passing inside of the spring. The construction of the disk C, however, and of the spring, may be widely varied without departing from the spirit of my invention. Any friction-disk provided with a central opening and with an arrangement for producing friction between it and a stationary part when the disk is rotated would be still within my invention. The form shown is, however, convenient and simple.

Attached to the upper part of the disk, and preferably by four pivots or by two long single pivots, F, are the pawls G G. These pawls, being horizontal, as shown, fall by gravity. The inner surfaces or edges of these pawls are angular in section, so that when the pawls are dropped the opening between them is substantially a square. The side of this square is less than the diagonal distance between the outer edges of the ribs on the twisted tube, while the diagonal of the square is greater than the distance between the edges of the ribs of the tube. It therefore follows that when the pawls are down the tube cannot be rotated within them if it were free to rotate. The pawls G G, however, move freely upward on their pivots F F; but they are so arranged that they cannot be thrown over so as to fall behind their pivots, their upward motion being arrested by some suitable contrivance—as, for instance, the soft buffer T.

The action of my apparatus can now be readily understood. The design of the structure is to cause the disk C to rotate against its friction when the tube B is pulled down, while the tube B can be raised freely without causing the rotation of the disk C.

In Fig. 2 the position of the apparatus while the tube is being drawn down is shown. In this position the lower surfaces of the pawls rest against the upper surface of the friction-disk, and the pawls are substantially horizontal, and the ribs of tube B engage with the pawls G G, and the effect upon the pawls and disk is substantially the same as though the tube B were rotated in the direction of the hands of a watch. In Fig. 2, if it were so rotated, it is apparent that the disk C would be

rotated with it. If, however, the tube B be elevated, the pawls G G will lift freely from their places, making the opening within them so large that the tube B can pass freely upward without rotating the disk C. When lifted, the shortest distance between the inside surfaces of the rectangular opening between the pawls will be sufficient to allow the passage of the tube B upward without rotating the disk. The hinged pawls should be made heavy enough to fall freely, although of course a spring might be employed, if desirable.

I have shown the best form of pawl known to me; but it is obvious that pawls differently constructed and arranged may be employed without departing from the spirit of my invention, which consists in causing the friction-disk to be rotated by a spirally-twisted rod or tube, by means of an intermediate pawl or pawls bearing directly against the spiral tube. The exact form and structure of the parts of my invention are therefore not essential; but that which is essential I point out in the claims hereto annexed.

I am aware that it is not broadly new in adjustable chandeliers to employ a spirally-ribbed rod passing through an annular pawl operating a friction device for retarding the downward movement of the rod, while at the same time freely permitting its upward adjustment, and to such construction alone I lay no claim; but

What I claim as my invention, and desire to secure by Letters Patent, is—

1. The combination, with a rod having a spiral rib upon it, of a friction device surrounding said rod, and carrying one or more

pawls pivoted thereto and adapted to engage with the spiral rib in one direction, thereby rotating the friction device, and to be disengaged from the spiral rib in the opposite direction, thereby leaving the friction device at rest, substantially as described. 40

2. The combination, with a rod provided with spiral ribs upon it, of a friction-disk surrounding said rod, and pawls movable toward and from and adapted to engage with the ribs on said rod in one direction, thereby rotating the friction-disk, and to be disengaged therefrom in the opposite direction, thereby leaving the disk at rest, substantially as described. 45

3. The combination, with a spirally-twisted rod having four opposite spiral ribs upon it, of a friction-disk surrounding said rod and carrying two horizontal pivoted pawls adapted to surround said rod and engage therewith when the rod is depressed, thereby rotating the friction-disk, but to be elevated and disengaged from the rod when said rod is elevated, thereby leaving the friction-disk at rest, 50 substantially as described.

4. The combination, with the spiral tube B, sliding vertically, but prevented from rotation, of the tube H, carrying supporting-drum A, likewise prevented from rotation, and friction-disk C, held against the drum A by spring D, and provided with pawls G G, forming substantially a rectangular inner opening when depressed, substantially as described. 65
